(57) **CLAIM**

The ornamental design for a computer mouse, as shown and described.

DESCRIPTION

FIG. 1 is a top plan view of a computer mouse;
FIG. 2 is a front elevation view of the computer mouse;
FIG. 3 is left side elevation view of the computer mouse;
FIG. 4 is a right side elevation view of the computer mouse;
FIG. 5 is rear elevation view of the computer mouse;
FIG. 6 is right rear perspective view of the computer mouse;
FIG. 7 is left rear perspective view of the computer mouse;
FIG. 8 is a rear perspective view of the computer mouse; and,
FIG. 9 is a top plan view of the computer mouse being used by the hand of a user.

The broken lines shown on the computer mouse are not part of the claimed invention.

In FIG. 9, the hand of a user is shown in broken lines and is not part of the claimed invention.
